United States Patent Office

Des. 224,076

Patented June 27, 1972

224,076

SIGN

Jack A. McMillan, Oklahoma City, Okla., assignor to
Circustine, Inc., Oklahoma City, Okla.

Filed Dec. 14, 1970, Ser. No. 26,469

Term of patent 14 years

Int. Cl. D20—03
U.S. Cl. D96—12

FIG. 1 is an elevational view taken from one side of a sign showing my new design, the opposite side being a mirror image of the side shown;

FIG. 2 is an elevational view taken from one end thereof, the opposite end being the same as the end shown.

FIG. 3 is a top view thereof.

I claim:

The ornamental design for a sign, as shown and described,
